UNITED STATES PATENT OFFICE.

WILLIAM D. KYLE, OF MILWAUKEE, WISCONSIN.

INSULATOR-BRACKET.

1,311,977.

Specification of Letters Patent. Patented Aug. 5, 1919.

Application filed August 2, 1915. Serial No. 43,079.

To all whom it may concern:

Be it known that I, WILLIAM D. KYLE, a citizen of the United States, and resident of Milwaukee, in the county of Milwaukee and 5 State of Wisconsin, have invented new and useful Improvements in Insulator-Brackets, of which the following is a description, reference being had to the accompanying drawings, which are a part of this specification.

10 This invention relates to improvements in insulator brackets.

It is one of the objects of this invention to provide an insulator bracket more particularly adapted for attachment to the side of 15 a support and having an arm projecting at an angle to hold the insulator in upright or other position.

A further object of the invention is to provide an insulator bracket which may be 20 screwed to the side of the support and then locked in this position and prevented from turning by means of a small nail or other holding means.

25 A further object of the invention is to provide an insulator bracket having a novel means for holding and locking the insulating spool on the arm of the bracket.

30 A further object of the invention is to provide an insulator bracket in which the parts are so shaped as to provide the maximum bracing effect in a very simple manner.

35 A further object of the invention is to provide an insulator bracket which is of simple construction, is strong and durable, can be manufactured at a minimum cost and is well adapted for the purpose described.

40 With the above and other objects in view the invention consists of the improved insulator bracket and its parts and combinations as set forth in the claim, and all equivalents thereof.

45 In the accompanying drawing in which the same reference characters indicate the same parts in all of the views:

Figure 1 is a side view of the improved insulator bracket, parts being shown in section to illustrate interior construction;

Fig. 2 is a horizontal sectional view thereof taken on line 2-2 of Fig. 1; and

50 Fig. 3 is a vertical sectional view thereof taken on line 3-3 of Fig. 1.

Referring to the drawing the numeral 5 indicates the base portion, 6 the attaching screw, 7 the curved arm and 8 the insulating spool mounted thereon. The base portion

is of disk like form and is provided with diametrically oppositely positioned tangential slots 9 to receive nails or screws (not shown) which are driven into the support to which the bracket is attached to hold said 60 bracket in its adjusted position and prevent the turning thereof. The arm which is of goose neck form, projects outwardly from the base portion and is then curved downwardly and upwardly in a half curve as indicated by the numeral 10 and its upper insulator holder portion 11 projects vertically in a straight line and terminates at a point above the upper edge of the base. The insulating spool 8 before mentioned is 70 mounted on the vertically extending portion and rests upon an annular shoulder 12 formed on the arm. The upper end portion of the arm immediately above the spool is provided with a transversely extending 75 opening 13 through which extends a locking pin 14, preferably formed of copper wire, which has its opposite end portions bent around the arm and securely locks the spool on the arm. As the pin may be easily 80 straightened and pulled out of the opening the spool may be quickly replaced in the event of breaking. The insulating spool is preferably formed of glass, porcelain or other like material and is provided with 85 grooved and flanged portions 8' to better protect the wires (not shown) connected to the spool and to more easily shed water.

The attaching screw 6 of the bracket is formed of steel and is connected to the 90 bracket by casting the bracket around the outer end or elongated head of the screw during the course of manufacture, the outer end portion of the screw being provided with annular grooves 14 into which the metal 95 of the bracket flows in casting and forms an intimate union between the two parts so that the parts are practically integral.

It will be noted that the base is comparatively of large diameter. This large diameter forms a large bearing surface against the support and serves as a brace to prevent the sagging or tilting downwardly of the bracket.

By having the attaching screw form part 105 of the bracket the bracket may be easily screwed into a support without the use of tools and the large bearing surface of the base serves to prevent the bracket from accidentally unscrewing from the support. 110

Furthermore the tangential slots provide a means for positively locking the bracket to the support when desired.

From the foregoing description it will be seen that the insulator bracket is of very simple construction and is well adapted for the purpose desired.

What I claim as my invention is:

An insulator bracket, comprising a comparatively large base member, a threaded member around one end portion of which the base member has been formed by casting to permit attachment to a support, said base member also having a downwardly and upwardly extending arm with its upper end portion extending in a straight line at approximately right angles to the threaded means, the lower end portion of the straight

part having an integral supporting shoulder formed thereon and the upper end of the arm provided with a transverse opening, an insulating spool having a bore through which the straight portion of the arm extends to permit the spool to rest directly upon the shoulder, and a wire pin extending through the transverse opening of the arm and having its end portions bent around the arm to lock the pin to the arm and the spool between the shoulder and the pin.

In testimony whereof, I affix my signature, in presence of two witnesses.

WILLIAM D. KYLE.
